UNITED STATES PATENT OFFICE.

CHARLES EISLER, OF IRVINGTON, NEW JERSEY, ASSIGNOR TO WESTINGHOUSE LAMP COMPANY, A CORPORATION OF PENNSYLVANIA.

MEANS FOR INCREASING THE EFFICIENCY OF HOT-SWAGING MACHINES.

1,324,886.

Specification of Letters Patent. Patented Dec. 16, 1919.

Application filed March 28, 1918. Serial No. 225,309.

To all whom it may concern:

- Be it known that I, CHARLES EISLER, a citizen of the United States, and a resident of Irvington, in the county of Essex and 5 State of New Jersey, have invented a new and useful Improvement in Means for Increasing the Efficiency of Hot-Swaging Machines, of which the following is a specification.
- 10 This invention relates to machines adapted for the hot swaging of metals and particularly to means for increasing the production capacity of swaging machines of this type.
- 15 In swaging machines now commonly in use, where metals and alloys thereof are worked in a hot state, the spindle carrying the rotative parts of the head including the swaging dies, becomes very hot. The heating 20 of this element greatly increases the wear thereon and the machine must be operated at a considerably lower speed than would be necessary if this heating effect were eliminated. It has heretofore been 25 proposed to place water-cooled jackets upon the outside of swaging machines of certain standard forms. Such devices not only gives the machines a cumbersome appearance but do not function very efficiently be- 30 cause the cooling medium circulated therethrough is not sufficiently close to the head shafts or spindles to be capable of exerting any substantial cooling effect thereon.
- It is one of the objects of this invention 35 to provide means whereby the spindle carrying the swaging dies may be rapidly cooled, with a consequent decrease in wear and a resultant increase in production effected by an increase in the speed of operation of the 40 machine.
- In accordance with this invention, a hollow chamber is provided as an integral part of the head of the swaging machine and is located in close proximity to the rotative 45 spindle carrying the swaging dies. This chamber or jacket is provided with an inlet and an outlet positioned at points relatively close to each other and an intermediate barrier to insure a maximum circulating 50 area for the water passing through the jacket. This construction affords a continuous circulation of water in close proximity to the spindle, whereby it may be rapidly cooled, thus reducing the wear 55 thereon and simultaneously permitting the
- operation thereof at a much higher speed, resulting in increased production.
- The nature of the means by which the foregoing and other more specific objects of the invention are accomplished will appear from the following detailed description. 60
- The invention is illustrated in the accompanying drawings in which Figure 1 is an elevation, partly in section, of a swaging machine embodying the invention; and Fig. 2 is an end front view of the machine shown in Fig. 1.
- Like reference characters refer to like parts throughout the several figures. 70
- In the machine shown in the drawing, only so much is illustrated as is thought necessary to disclose the invention. In this disclosure is shown a head portion 1 suitably attached to a supporting base 2. The 75 head portion 1 is provided with a hollow shaft or spindle 3 which is axially mounted within a cylindrical casting 4. On the right-hand or front side of the head 1 are mounted the usual swaging dies and the 80 associated mechanism for operating the same, these elements not being shown in detail, as they are well known to those skilled in the art. On the left-hand side of the spindle 3 is rigidly mounted a pulley 5 adapted to accommodate a belt for rotating the spindle 3. The casting 4 is provided with a hollow chamber or jacket 6 which extends substantially the full distance 85 around the inner portion of the casting and is positioned relatively close to the spindle 3. To reinforce the adjacent surfaces forming the jacket 6, strut members 7, preferably cast integral with the casting 4, are located at convenient places, and one of these strut 90 members 7 may be provided with an aperture 8 leading from the exterior of the casting 4 to the interior thereof, said aperture being designed to function as an oil-cup for lubricating the spindle 3, when rotating. 95
- The chamber or jacket 6 is provided with an inlet orifice 9 and an outlet orifice 10 which are suitably threaded to permit of the attachment thereto of water pipes (not shown) so as to permit the continuous free 100 circulation of the water through the jacket 4 whenever desired. To insure a circulation of water entirely around the jacket 6, a barrier 12 is provided intermediate the inlet and outlet orifices 9 and 10. 105
- 110

The pulley 5 is connected, by means of a belt, to a source of power and is caused to rotate the spindle 3 at a high speed. As is well understood by those skilled in the art of hot swaging, the rotation of the spindle 8 sets in motion the swaging dies contained in the front or right-hand side of the head 1, and the work is passed through the machine in a heated condition from right to left. As the work passes through the machine, on account of the action of the dies and their initial heated condition, considerable heat is conducted to that portion of the spindle 3 immediately following or contiguous to the swaging dies, with the consequent effect that this portion of the spindle is excessively heated. If the spindle 3 were rotated at a very high speed, its temperature would be increased much more, in the absence of any cooling agency other than normal radiation, and, if the swaging machine were operated in this condition for any considerable length of time, the wear on the spindle 3 would be very great, resulting in high depreciation of it and adjacent parts which, in a short time, would necessitate replacement thereof, with the consequent loss in production due to the idleness of the machine during the time required for replacing the aforesaid parts. However, by means of the water-cooled jacket 6, located in close proximity to the spindle 3 and having sufficient capacity to permit the circulation of a considerable volume of water over a relatively large area, the temperature of the spindle may be kept within safe operating limits, although rotated at as high speed as may be dictated by approved practice, considering the design of the parts comprising the swaging machine.

From the above description it will be apparent that the structure contemplated by this invention provides for a continuous circulation of water or other cooling liquid in close proximity to the rotatable spindle carrying the swaging dies, which effects the efficient cooling of the said spindle, thereby decreasing the wear thereon, permitting the rapid rotation thereof, etc. It is obvious that, if my invention were embodied in a standard swaging machine, it would be possible to operate such modified machine at the speed for which it was originally designed and at a greatly reduced depreciation factor which would compensate for the difference in production capacity when operated at this lower speed and at maximum speed, by resulting decrease in the cost maintenance and loss occasioned by idleness of

the machine during repairs. In other words, the speed of operation may resolve itself into a question of continuous running at a fair speed, or interrupted running at an excessive speed, the determination of a particular speed being dependent upon a question of policy and the conditions of a given case. From experience I have learned that a standard form of swaging machine, when modified in accordance with my invention, 65 may be operated continuously at 850 revolutions per minute, the speed for which it was originally designed, or the same machine may be operated at a speed of from 2700 to 3000 revolutions per minute, with a resultant greater depreciation factor than in the first instance.

While I have described my invention with reference to the specific embodiments shown, it is obvious that various changes 80 in detail may be made without departing from the spirit and scope thereof.

Claims:—

1. A swaging machine having a water-cooled jacket formed internally of the machine head, and a spindle journaled within said head and arranged to be influenced by the cooling effect of said jacket. 85
2. In a swaging machine, the combination with swaging dies and mechanism for actuating the same, of a hollow spindle, means for rotating the same, a water-cooled jacket integrally formed internally of the machine head and having an opposing surface in close proximity to said spindle, whereby the 90 latter may be rapidly cooled.
3. In a swaging machine, a head, a water-cooled jacket integrally formed internally of said head, a spindle journaled within said head and arranged relatively close to the opposing surface of said jacket, whereby the said spindle may be cooled to good effect. 100
4. In a swaging machine, a head, a water-cooled jacket integrally formed internally of said head, a spindle journaled within said head and arranged adjacent one of the surfaces of said water jacket, supporting members for reinforcing the walls of said jacket, one of said supporting members being 105 adapted to function as an oil passage to said spindle, and means for providing a continuous circulation of water through said jacket, whereby said spindle may be rapidly cooled. 110

In testimony whereof, I have hereunto subscribed my name this 7th day of March, 1918.

CHARLES EISLER.
